(57) **CLAIM**

We claim the ornamental design for a model vehicle pivoting axle carrier, as shown and described.

DESCRIPTION

FIG. 1 is an upper, left, front perspective view of a model vehicle pivoting axle carrier, according to our new design; FIG. 2 is a left elevation view thereof; FIG. 3 is a right elevation view thereof; FIG. 4 is a rear side elevation view thereof; FIG. 5 is a front side elevation view thereof; FIG. 6 is an upper plan view thereof; and, FIG. 7 is a lower plan view of the model vehicle pivoting axle carrier.

In the drawings, the broken lines showing of features of the model vehicle pivoting axle carrier form no part of the claimed design.

In the drawings, a first embodiment of the left model vehicle pivoting axle carrier is shown. It is understood that a second embodiment of the right model vehicle pivoting axle carrier is a mirror image thereof.
